UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

FRICITION DOOR HOLDER.

Application filed July 15, 1925. Serial No. 43,722.

To all whom it may concern:

Be it known that I, NORMAN B. HURD, a citizen of the United States of America, residing at New Britain, Connecticut, have 5 invented a new and useful Friction Door Holder, of which the following is a specification.

My invention relates to a friction door holder.

10 It is an object of the invention to improve the construction of a friction door holder and to provide one which will be serviceable in use and which can be manufactured relatively cheaply.

15 It is another object to provide a door holder which may be used without alteration or inverting for either a right or left hand opening door. Other objects will be apparent upon the reading of the following specification.

Briefly stated, in the preferred form of the invention, I employ two arms one to be attached to a door casing and the other to be attached to a door. If desired, a 25 door closer may be used in connection with my improved door holder. The two arms are pivotally connected together and a friction member is adapted to frictionally coact with the arms for holding the door in position. When the device is used for a right hand opening door, the friction member frictionally coacts with one arm while when the device is used on a left hand opening door, the friction member frictionally coacts with the other arm for holding the door in position. It is not necessary with my improved door holder to turn the same over or make any changes when using the same on a right or on a left hand 30 opening door. The device may be readily and simply adjusted so as to hold the door in any desired position within the range of adjustment.

In the drawings which show, for illustrative purposes only, a preferred form of the invention—

Fig. 1 is a top plan view of a door holder applied and illustrating features of the invention;

50 Fig. 2 is an enlarged side view in partial section of the friction holder shown in Fig. 1;

Fig. 3 is a bottom plan view of the device shown in Fig. 2.

In the form shown, I employ two arms 55 5—6 one of which may be pivotally secured to a door casing or wall 7, while the other may be pivotally secured to a door 8 or, if desired, to a door closer 9 thereon. The arms are provided with friction faces 60 10—11 for coaction with complementary friction faces on which I will term a friction block 12 interposed between the two arms. A pivot member, such as a bolt 13, pivotally connects the two arms together 65 and holds the friction block 12 in place. The bolt 13 may be non-rotatably secured to one arm as by means of a square shoulder 14 formed thereon and fitting within a correspondingly shaped bore through the arm. 70 A nut 15 may be threaded on one end of the bolt 13 so as to permit of some adjustment as will be later described. The other end of the bolt 13 passes through a smooth bore in the other arm 5 and a nut 75 16 is threaded thereon. If desired, a lock washer 17 may be interposed between the nut 16 and the arm 5. The washer may have a lug or tongue 18 projecting from the bore therethrough, which lug is slidable 80 in a keyway or groove 19 extending longitudinally of the bolt 13. This lock washer is for the purpose of causing the nut 16 to turn with the bolt so as to avoid the danger of having the nut 16 become accidentally loosened when the device is in use. Since the opposite end of the bolt is square as at 14, the nut 15 will also turn 85 with the bolt and with the arm 6. The intermediate portion 20 on the bolt 13 is 90 screw-threaded and the friction block 12 is provided with an internal thread fitting on the threaded portion 20 so that in rotating the friction block and bolt relatively to each other, the friction block will move 95 longitudinally of the bolt in one direction or the other so as to frictionally coact with either the friction surface 10 on the arm 6 or with the friction surface 11 on the arm 5.

100 The friction block is connected to one or the other or to both of the arms. In the preferred form shown, the block is provided with an extension or arm 21 which may be slotted as indicated at 22. Links 105 23—24 may be pivotally connected to the arms 6—5 respectively as by means of pins or rivets 25—26 and the opposite ends of

the links may be pivoted to each other by means of the pin or rivet 27 which latter may be slidable in the slot of 22 so as to cause the pivoted together ends of 6 the links to move the arm 21. The operation of the device is as follows:

With the arms connected, for example as shown in Fig. 1, when the door is closed, the friction block 12 will be spaced from say 10 the lower friction face 11 on the arm 5 and the arms will lie at small angle to each other, the arm 21 substantially bisecting the angle between the two arms. Now, when the door is opened, the arms move to an increasing 15 angle with each other and due to the link connection, the block 12 will rotate in an anti-clockwise direction as viewed in Fig. 1, and in so doing will tend to ride upwardly on the threaded portion 20 of the bolt. 20 However, due to the link connection the block 12 will rotate at approximately half the speed of the bolt 13 and consequently the bolt rotates at approximately double the speed of the block and the net movement of 25 the block will be toward the arm 5 until it contacts with the friction face 11 thereon and the door will then be held in adjusted position. If it is desired to hold the door in a wider open position, the nut 16 is backed 30 off slightly so as to permit a further rotation of the block 12 before it engages the friction face 11. Obviously by varying the position of the nut 16, the position at which the door is held open may be correspondingly varied.

As will be clear from the drawings, the arms 5-6 may be folded together as shown in Figs. 2 and 3 and, therefore, the arm 6, when loosened from the door could be rotated 40 in a clockwise direction as viewed in Fig. 1, and rotated 180 degrees and during this rotation the block 12 and arm 21 thereon would be rotated in the same direction substantially 90 degrees. Obviously then with 45 this possible movement the door holder may be used on either a right or left hand opening door. When used on a door opening opposite to that shown in Fig. 1, the friction face 10 on the arm 6 would be engaged by 50 the corresponding friction face on the block 12 and adjustment of the position at which the door is held open would be effected by screwing up on or backing off on the nut 15 in a manner similar to that heretofore 55 described.

It will therefore be seen that by my improved friction door holder, I am enabled to hold open a door which opens right or

left handed and this without turning the holder upside down as required with some 60 holders now on the market, and without making any substantial changes or adjustments other than perhaps adjusting the nut 15 or the nut 16 so as to hold the door in the desired position. A very accurate adjustment may be secured and the parts will be caused to operate positively and reliably and there are few parts to get out of order. The door holder may be employed in connection with any suitable form of door 70 closer but I do not wish to be limited to such combined use since my door holder may be employed merely for holding open a door which is manually closed.

While the invention has been described in some detail, I do not wish to be limited to the form shown since changes may be made within the scope of the invention as shown in the appended claims.

I claim:

1. In a friction door holder, a pair of arms having friction faces thereon, a friction block adapted to frictionally engage said faces, a bolt connecting said arms and in screw threaded engagement with said friction block whereby when the bolt and friction block are relatively rotated in one direction, the block will contact with the friction face on one arm and, when rotated in the opposite direction, the block will contact with the friction face on the other of said arms, and means for causing said block to rotate at a different speed than said arms as the latter are swung to and fro.

2. In the combination defined in claim 1 and means for connecting said block to the other of said arms whereby the movement of said block will be influenced by the relative movement of said two arms.

3. In a friction door holder, a pair of arms having friction faces thereon, a friction block interposed between said arms and adapted to frictionally engage said friction faces, a bolt non-rotatably secured to one arm and connecting said arms and friction block, said friction block being in screw threaded engagement with said bolt, a pair of links connected to each other and having a sliding connection with said block, said links being connected to said arms, whereby upon a relative rotation of said arms, said links will cause said friction block to rotate relatively to said arms for causing the block to move on said bolt to engage one of said friction faces.

NORMAN B. HURD.
